(57) **CLAIM**

The ornamental design for a hip and valley vent for a roof, as shown and described.

DESCRIPTION

FIG. 1 is a perspective view of a hip and valley vent for a roof showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a view of the hip and valley vent for a roof in a partially folded orientation.

The hip and valley vent for a roof is shown with a symbolic break. The appearance of any portion of the hip and valley vent for a roof shown between the break lines forms no part of the claimed design.

The broken lines in the drawings depict portions of the hip and valley vent for a roof that form no part of the claimed design.
